Primary Examiner — Jennifer L Watkins(74) *Attorney, Agent, or Firm* — HOVEY WILLIAMS LLP(57) **CLAIM**

The ornamental design for a wearable intranasal device, as shown and described.

DESCRIPTION

FIG. 1 is a front elevational view of the wearable intranasal device showing my new design.

FIG. 2 is a top plan view thereof.

FIG. 3 is a right side elevational view thereof, the left side being a mirror image thereof.

FIG. 4 is a bottom plan view thereof; and,

FIG. 5 is a perspective view thereof.

The broken lines show structural elements which form no portion of the claimed invention.

1 Claim, 5 Drawing Sheets(56)
